EXPLOSIVELY ACTUATED TOOL

Robert Temple, Jr., Pittsburgh, Pa.

Application May 11, 1937, Serial No. 141,935

17 Claims. (Cl. 164—56)

This invention relates to tools actuated by explosive means and more particularly to apparatus of this character particularly adapted for use under water, as, for example, in cutting cables.

- 5 It is the general object of my invention to provide an improved explosively actuated tool which is particularly adapted for under-water operations and for cutting strand material, such as cables, rods, pipes and the like.
- 10 Another object of my invention is the provision of a tool operated by the force of a detonated explosive charge, such as a blank cartridge, and wherein the tool can be readily reloaded under water.
- 15 Another object of my invention is to provide a relatively small and light weight apparatus which is readily portable but strong and sturdy, which is adapted to cut strand materials, such as cables, wires, rods, tubes, pipes or other similar members.
- 20 Another object of my invention is the provision of a sealed unit for explosively actuated tools, which unit is readily replaceable and includes an explosive charge, breech and piston.

For a better understanding of my invention, reference should be had to the accompanying drawings wherein Fig. 1 is a side elevation of one form of apparatus constructed in accordance with the principles of my invention; Fig. 2 is a vertical cross-sectional view taken on line II—II of Fig. 1; Fig. 3 is a side elevation of another embodiment of my invention; Fig. 4 is a vertical cross-sectional view of the apparatus illustrated in Fig. 3; Fig. 5 is a bottom plan view of still another embodiment of my invention; and Fig. 6 is a vertical cross-sectional view taken on line VI—VI of Fig. 5.

While the principles of my invention, as hereinafter particularly disclosed, are broadly applicable to explosive tools of various kinds, such as employed to drive pins, dies, shears or other working tools, they are particularly beneficial in the provision of apparatus for cutting strand material, such as cables, rods, wires, pipes, tubes and like members, and hence have been specifically illustrated and will be so described.

In the form of my invention illustrated in Figs. 1 and 2, the numeral 10 indicates generally a C-shaped frame having opposed leg portions 12 and 14. The leg portion 12 is formed with a longitudinally extending bore which removably receives a female cutting die 16. The die 16 is held in operating position, as illustrated, by an appropriately shaped nut 18. Both the nut and die are formed with a longitudinal bore 20 which may be of any desired cross section but which is

ordinarily made round. The upper end of the die 16 and the corresponding side portions of the leg 16 are cut away to form a curved cradle or shoulders 22 so that a strand material to be severed, such as the cable C, can be moved between 5 the legs 12 and 14 and down against the shoulders 22 so that a short length of the cable is bridged across the bore 20 while supported by the cradle or shoulders 22 at the sides of the bore.

The leg 14 of the frame 10 is formed with a 10 longitudinal bore 30 which slidably receives a unit, indicated generally at 32, which unit includes a barrel 34 slidably receiving a piston 36 in turn slidably mounted upon a breech 38. The barrel 34 is formed with a reduced threaded portion 40 at one end upon which a complementarily threaded cap 42 is removably received. A sealing disc 46, ordinarily of copper, is clamped between the end of the barrel and the cap 42, as illustrated. The cap 42 is formed with a central 15 aperture as is the leg 14 so as to permit a male cutting die 48 carried by the piston 36 to move into the bore 20 of the female die.

The breech 38 of the unit 32 removably receives an explosive charge which is ordinarily in the 20 form of a blank cartridge 52. The other end of the barrel 34 is threaded as at 54, and removably receives an internally threaded cap 56. A sealing disc 58, usually formed of copper, is clamped between the cap 56 and the end of the barrel 34. 25 The unit 32 is removably held in the bore 30 of the leg 14 by a breech block 60 which is adjustably and removably secured in the end of the bore 30 which, in the embodiment of the invention illustrated, is accomplished by forming complementary threads 62 on the breech block and in the end of the bore 30. The breech block 60 is formed with a longitudinal aperture 64 which slidably receives a firing pin 66 normally urged toward the cartridge 52 by a compression spring 40 68, but adapted to be held in a retracted, cocked position by a pin 70 extending through the firing pin and engaging with the end of the breech block 60. Handles 72 upon the breech block facilitate removing or entering it in the bore 30 of 45 the leg 14.

In the operation of the form of my invention illustrated in Figs. 1 and 2 and just described, a unit 32 containing a blank cartridge 52 is positioned in the bore 30 of the leg 14 and the breech 50 block 60 is screwed tightly into place behind the unit. The firing pin 66 of the breech block is held in a retracted cocked position by the pin 70, as will be understood. The cable C to be cut is now placed in the female die 16 so that it rests 55

upon the cradle or shoulders 22 with a short portion of its length bridged across the bore 20. In firing the apparatus the pin 70 is removed which allows the firing pin 66 to be driven forcibly down towards the unit 32 by the compression spring 68. The end of the firing pin 66 engages with the sealing disc 68 and detonates the cartridge 52 without piercing or breaking the sealing disc. The detonation of the cartridge 52 tends to drive the piston 36 and the male cutting die 48 with high force and velocity towards the female cutting die.

However, initially the movement of the piston 36 and the male cutting die 48 is prevented by the engagement of the end of the male cutting die with the sealing disc 46. Only after the detonated cartridge 52 has built up a predetermined pressure, dependent upon the thickness of the sealing disc 46, is the sealing disc sheared at which time the piston 36 and male cutting die 48 are moved with the full force of the exploded cartridge down into engagement with the cable supported upon the female cutting die. The force behind the male cutting die and the momentum of the piston and die causes the male cutting die to shear a short length out of the cable placed on the female cutting die. The short plug so sheared falls down through the bore 20, as will be understood.

Once the apparatus has been operated, as just described, it is a relatively simple matter to pull back the firing pin 66, insert the pin 70, unscrew the breech block 60 and replace the unit 32 with another unit which has an unexploded cartridge 52 therein. This operation is readily accomplished by a diver when working with the apparatus under water, and since the unit 32 is completely self-contained and sealed, the apparatus can be repeatedly operated by a diver with any desired number of reloadings under water. It should be understood that if the apparatus is used in air, instead of providing a plurality of units 32, after each operation of the apparatus the particular unit containing the detonated cartridge can be disassembled by removing the caps 42 and 56 and replacing the sheared disc 46 and the detonated cartridge 52 with new ones, after which the caps can be again screwed in place and the unit is ready for installation in the apparatus.

In the embodiment of my invention illustrated in Figs. 3 and 4, the numeral 80 indicates generally a U-shaped frame having a longitudinal bore 82 which slidably receives a unit 84 which comprises a barrel 86, a piston 88, a male cutting die 89, and a breech 90 removably receiving an explosive charge, usually in the form of a blank cartridge 92. The barrel 86 is threaded at its upper end and receives an internally threaded cap 94 which functions to clamp a sealing disc 96, generally of copper, against the end of the barrel. The lower end of the barrel 86 is internally threaded and receives an externally threaded ring 98 which clamps a sealing disc 100 of copper against the other end of the barrel. The bore 82 of the frame 80 terminates in a shoulder 104 so that a female cutting die 106 is removably received at the lower end of the bore 82. The lower end of the frame 80 and the female cutting die 106 are formed with a longitudinally extending bore 108.

In order to receive a cable, rod, or other strand element to be cut, the frame 80 is formed with diametrically opposed longitudinally extending slots 112 which extend from the upper end thereof to a position laterally opposed to the female cut-

ting die 106. The female die 106 is formed with recesses at its side which provide shoulder portions 114 at the opposite sides of the bore 108 so that a cable received on the shoulder portions is carried in bridged relation across the bore 108.

In order to hold a cable on the shoulders 114, suitable means are provided which may take the form of a ring 118 which is rotatably mounted between an integral flange 120 formed on frame 80 and a ring 122 fixed to the lower end of the frame. The ring 118 is formed with diametrically opposed bayonet slots 124 which, as best seen in Fig. 3, can be turned into alignment with the slots 112 so that a cable can be introduced therethrough and positioned on the shoulders 114 and held in this position by turning the ring 118 slightly.

The unit 84 is removably held in the frame 80 by a cap 130 which is mounted in a quickly releasable manner upon the upper end of the frame. This is preferably accomplished, as illustrated, by the provision of a breech block joint indicated at 132 between the cap and the upper end of the frame. The cap 130 is provided with an internally threaded longitudinally extending aperture which receives the threaded end of a breech block 136 having handles 138 whereby the breech block can be screwed into and out of the cap 130. The breech block 136 is formed with a longitudinal bore 140 slidably receiving a firing pin 142 normally held in a retracted position by a releasable pin 144 but urged toward the unit 84 by a compression spring 146.

In the operation of the apparatus illustrated in Figs. 3 and 4 with the parts in the position illustrated and a cable received in the female cutting die 106, the pin 144 is removed, whereupon the compression spring 146 drives the firing pin 142 against the sealing disc 96 so that without rupturing the disc the firing pin detonates the cartridge 92. The detonation of the cartridge tends to drive the piston 88 and the male cutting die 89 towards the female cutting die 106. The end of the male cutting die 89, however, is in engagement with the disc 100 and is held against movement until the force of the detonated blank cartridge reaches a predetermined value at which time the disc 100 is sheared to allow the piston 88 and the male cutting die 89 to be driven with high force and momentum against the cable carried in the female cutting die. The male cutting die shears a relatively short length of plug from the cable which is forced out of the bore 108. A collar 101 of soft metal positioned between the disc 100 and the female die 106 cushions the stopping of the piston 88 and prevents breakage of any of the apparatus parts.

The breech block 136 is now loosened in the cap 130 and the cap is turned through a small arc relative to the frame 80 and then lifted off to expose the unit 84. The unit can be lifted out and replaced by another unit containing an unfired cartridge 92 and a solid sealing disc 100 and the cap 130 and breech block 136 replaced by reversal of the operations just described to reassemble the apparatus in firing position. It will be understood that the unit 84 can be readily replaced under water so that the apparatus is adapted for continuous under water operation. When used above water and in air the unit 84 can be taken apart by removing the collar 101 and the cap 94 and providing a new disc 100 and cartridge 92, as will be understood.

In the form of my invention illustrated in Figs. 5 and 6, the numeral 150 indicates a barrel having a threaded end received in a suitably tapped aper-

ture in a plate 152. The barrel 150 slidably receives a unit 154 which includes a tube 158, a piston 158, and a breech 160 removably receiving a blank cartridge 162. The piston 158 carries a 5 male cutting die 164.

The ends of the unit 154 are sealed by discs 168 and 170 of copper which are held against the ends of the tube as by a collar 172 and a cap 174, respectively. The lower end of the unit 154 engages with the bottom of the recess in which the barrel 150 is threaded and the other end of the unit 154 engages with a breech block 178 which is formed with an external thread received in a suitably threaded end of the barrel. The breech block 178 is formed with handles 180 which facilitate screwing it into or out of the end of the barrel 150. The breech block 178 is formed with a longitudinal bore which slidably receives a firing pin 182 which is normally held in a retracted cocked position by a pin 184 but which is urged toward the unit 150 by a compression spring 186.

Threaded into suitable tapped holes in the plate 152 are heavy cap screws 190 which extend through a hole and an arcuate slot 191 in a plate 25 192 adapted to be held in spaced parallel relation to the plate 152. The cap screws 190 are adapted to clamp a female cutting die 194 between the plates 152 and 192. The female cutting die 194 and the plate 192 are formed with longitudinal 30 apertures 196 and the female cutting die is provided with diametrically opposed recesses which form shoulder portions 198 at opposite sides of the bore 196.

In the operation of the embodiment of the invention just described and shown in Figs. 5 and 6, the cap screws 190 are loosened and the plate 192 is swung laterally about one of the cap screws which is permitted by the slot 191, and the female cutting die 194 is removed from between the 40 plates 152 and 192. The strand material marked R, such as a rod, cable, tube, pipe, or the like, is then placed in the end of the female cutting die so that the member R rests on the shoulders 198 and has a portion bridged across the bore 196. 45 The female cutting die carrying the member R is then placed back between the plates 152 and 192. The plate 192 is swung back in its original position and the cap screws 190 are tightened to secure the female cutting die and the member R firmly between the plates.

Assuming that the barrel 150 has a unit 154 therein in the position illustrated, then the apparatus is fired by merely removing the pin 184 which allows the firing pin 182 to be driven forcibly down against the disc 170 to detonate the cartridge 162. The piston 158 and male cutting die 164 are held against movement until a predetermined pressure has been reached by the detonated cartridge. The predetermined pressure is adjustable by varying the thickness of the sealing disc 168 which holds the male cutting die and piston against movement. Once the desired pressure has been built up the male cutting die 164 shears through the sealing disc 168 and is driven 60 with high force and momentum against the member R carried by the female cutting die 194. The male cutting die 164 shears a short plug or section from the member R, which plug falls through the bore 196. A collar or ring 171 of relatively 65 soft metal, such as copper, brass, or the like, positioned between the upper end of the female die and the end of the piston 158, acts as a cushion at the end of the travel of the piston so that possible shock or breakage of the parts is prevented.

70 Once the apparatus has been operated as just

described, it is a relatively simple matter to remove the breech block 178 and then remove the unit 154 so that a new unit can be positioned in the barrel 150. Screwing the breech block back in position after cocking the firing pin 182 reestablishes the apparatus in the operating position illustrated in Fig. 6. This reloading operation as just described is readily accomplished under water as will be recognized, and it is also possible to reload above water, as for example in air, by a similar replacement of the unit 154. It may be found advisable, however, in certain instances, to merely take the unit 154 apart by removing the cap 174 and ring 172 and replacing the cartridge 162 and sealing disc 168.

15 It should be understood that in any of the forms of my invention illustrated the exact shape of the female and male cutting dies can be varied within wide limits so as to adapt the apparatus for cutting, punching or shearing operations of 20 various kinds. Likewise, I contemplate employing the units as above described in conjunction with tools for performing other than cutting or punching operations as, for example, the driving of dies, piercing pins or rivets and the like, 25 and that moreover the exact type of frame unit holding means, breech block, firing pin, die mountings, and the like can be varied within wide limits.

30 From the foregoing description it must be recognized that the objects of my invention have been achieved by the provision of explosively actuated apparatus for performing work, which apparatus is particularly adapted to under water operation, and in which loading and repeated use 35 under water can be readily accomplished. The principles of my invention are broadly applicable to the operation of tools of various kinds but are particularly beneficial in cutting and punching operations. The apparatus is relatively light and 40 portable and yet is strong and rugged and is adapted to be operated over long periods without maintenance or repair and can be operated by the ordinary workman without prolonged instructions or technical training.

45 While in accordance with the patent statutes at least one particular embodiment of the invention has been specifically illustrated and described, it should be appreciated that my invention is not limited thereto or thereby but is defined in the appended claims.

I claim:

1. An explosively actuated apparatus including a barrel, means spaced from but in alignment with the barrel and integral therewith and 55 adapted to receive the material worked, a unit slidably received completely in the barrel, said unit comprising a tube, a breech within the tube adapted to removably receive a blank cartridge, a piston slidably mounted in the tube, a tool carried by the piston, sealing discs of relatively thin metal removably clamped at the ends of the tube, the tool being in shearable engagement with the disc at the work-receiving end of the tube and held against movement thereby, a breech block 60 removably positioned over the end of the barrel opposite the work-receiving means and holding the unit against movement in the barrel, and means associated with the breech block for detonating a blank cartridge carried by the unit.

70 2. An explosively actuated apparatus including a barrel, means spaced from but in alignment with the barrel and integral therewith and adapted to receive the material worked, a unit slidably received in and completely surrounded and sup- 75

ported by the barrel, said unit comprising a tube, a breech associated with the tube adapted to removably receive a blank cartridge, a piston slidably mounted in the tube, a tool carried by the piston, sealing discs removably clamped at the ends of the tube, a breech block removably positioned over the end of the barrel opposite the work-receiving means and holding the unit against movement in the barrel, and means associated with the breech block for detonating a blank cartridge carried by the unit.

3. An explosively actuated apparatus comprising a barrel, means spaced from but in fixed alignment with the barrel and adapted to receive the material worked, a unit slidably received in the barrel, said unit including a breech adapted to removably receive a blank cartridge, a piston slidably associated with the breech, a tool carried by the piston, sealing discs removably clamped at the ends of the unit, the tool being in shearable engagement with the disc at the work-receiving end of the unit and held against movement thereby until a predetermined force on the disc has been exceeded, a breech block removably positioned over the end of the barrel opposite the work-receiving means and holding the unit against movement in the barrel, and means associated with the breech block for detonating a blank cartridge carried by the unit.

30 4. An explosively actuated apparatus comprising a barrel, means spaced from but in alignment with the barrel and integral therewith and adapted to receive the material worked, a unit slidably received in the barrel, said unit including a breech adapted to removably receive a blank cartridge, a piston slidably associated with the breech, sealing discs removably clamped at the ends of the unit, a breech block removably positioned over the end of the barrel opposite the work-receiving means and holding the unit in fixed relation in the barrel, and means associated with the breech block for detonating a blank cartridge carried by the unit.

45 5. An explosively actuated apparatus including a barrel, integral means spaced from but in alignment with the barrel and adapted to receive the material worked, a unit slidably received in the barrel and completely surrounded and supported thereby, means sealing the ends of the unit against fluid leakage, a breech block removably positioned over the end of the barrel opposite the work-receiving means and holding the unit in fixed position in the barrel, and means associated with the breech block for detonating a blank cartridge carried by the unit.

55 6. In combination, a C-shaped frame having opposed legs in alignment, one of said legs having a bore therethrough terminating in a reduced shoulder adjacent the other leg, a unit removably received in the bore, a breech block removably holding the unit in fixed relation in the bore, a female cutting die removably carried on the other leg in alignment with the unit, said unit including a breech adapted to receive an explosive charge, a piston slidably mounted in the unit for movement longitudinally thereof upon the detonation of the explosive means, a male cutting die carried by the piston for movement into working relation with the female die upon movement of the piston, means sealing the unit against fluid leakage into it and at least part of the sealing means holding the piston against movement until a predetermined force has been exceeded by the detonated explosive charge, and

means carried by the breech block for detonating an explosive charge carried by the unit.

7. In combination, a frame having opposed legs in alignment, one of said legs having a bore therethrough terminating in a reduced shoulder adjacent the other leg, a unit removably received completely in the bore and supported thereby against fracture, a breech block removably holding the unit in the bore and fixedly against the shoulders, work-receiving means removably carried on the other leg in alignment with the unit, said unit including a breech adapted to receive an explosive charge, a piston slidably mounted in the unit for movement longitudinally thereof upon the detonation of the explosive means, a material working tool carried by the piston for movement into working relation with the material positioned on the work-receiving means upon movement of the piston, means sealing the unit against fluid leakage therein and at least part of the sealing means holding the piston against movement until a predetermined force has been exceeded by the detonated explosive charge, and means carried by the breech block for detonating an explosive charge carried by the unit.

8. In combination, a frame having opposed legs in alignment, one of said legs having a bore therethrough terminating in a reduced shoulder adjacent the other leg, a unit removably received in the bore and completely surrounded and supported thereby, a breech block removably holding the unit fixedly in the bore, work positioning means carried on the other leg in alignment with the unit, said unit including a breech adapted to receive an explosive charge, a piston slidably mounted in the unit for movement longitudinally thereof upon the detonation of the explosive means, a working tool carried by the piston for movement into working relation with the work positioning means upon movement of the piston, means sealing the unit against fluid leakage therein and at least part of the sealing means holding the piston against movement until a predetermined force has been exceeded by the detonated explosive charge, and means carried by the breech block for detonating an explosive charge carried by the unit.

9. In combination, a frame having opposed legs in alignment, one of said legs having a bore therethrough terminating in a reduced shoulder adjacent the other leg, a unit removably received in the bore against the shoulder, a breech block removably holding the unit fixedly in the bore, work positioning means carried on the other leg in alignment with the unit, said unit including a breech adapted to receive an explosive charge, a piston slidably mounted in the unit for movement longitudinally thereof upon the detonation of the explosive means, a working tool carried by the piston for movement into working relation with the work positioning means upon movement of the piston, means sealing the unit against fluid leakage, means holding the piston against movement until a predetermined force has been exceeded by the detonated explosive charge, and means carried by the breech block for detonating an explosive charge carried by the unit.

10. In combination, a frame having opposed legs in alignment, one of said legs having a bore therethrough terminating in a reduced shoulder adjacent the other leg, a unit removably received in the bore against the shoulder, a breech block removably holding the unit in the bore in fixed relation against the shoulder, work positioning means

- carried on the other leg in alignment with the unit, said unit including a breech adapted to receive an explosive charge, a piston slidably mounted in the unit for movement longitudinally thereof upon the detonation of the explosive means, a working tool carried by the piston for movement into working relation with the work positioning means upon movement of the piston, and means carried by the breech block for detonating an explosive charge carried by the unit. 5
11. In combination, a frame having opposed legs in alignment, one of said legs having a bore therethrough terminating in a reduced shoulder adjacent the other leg, a unit removably received in the bore, a breech block removably holding the unit in the bore in fixed relation against the shoulder, work positioning means removably carried on the other leg in alignment with the unit, means sealing the unit against entrance of fluid, 10 and means carried by the breech block for detonating an explosive charge carried by the unit. 15
12. In combination, a U-shaped frame having a longitudinal bore terminating in a shoulder, a female cutting die removably positioned on the shoulder, means for clamping work on the female cutting die, a unit slidably received in the bore and positioned in engagement with the die, a breech block removably mounted on the end of the frame opposite the die, means associated with 20 the breech block for detonating an explosive charge carried by the unit, said unit including a breech adapted to removably receive an explosive charge, a piston mounted for movement to and from the breech, a male cutting die carried by the piston, and means sealing the ends of the unit and normally holding the piston against movement but shearable when the expanding force of the detonated explosive charge reaches a desired maximum. 25
13. In combination, a frame having a longitudinal bore terminating in a shoulder, work receiving means positioned on the shoulder, means for clamping work on the work receiving means, a unit slidably received in the bore and positioned in engagement with the work receiving means, a breech block removably mounted on the end of the frame opposite the work receiving means, means associated with the breech block for detonating an explosive charge carried by the unit, said unit including a breech adapted 30 to removably receive an explosive charge, a piston mounted for movement to and from the breech, a working tool carried by the piston, and means sealing the ends of the unit and normally holding the piston against movement but shearable when the expanding force of the detonated explosive charge reaches a desired maximum. 35
14. In combination, a barrel, a plate secured in transverse perpendicular relation to the bar- 40
- rel, a second plate, a female cutting die, cap screws for removably holding the plates in spaced parallel relation with the female die therebetween in alignment with the barrel, a unit removably positioned in the barrel, a breech block releasably holding the unit in the barrel, and means associated with the breech block for detonating an explosive charge carried by the unit, said unit including a tube, sealing discs removably clamped at the ends of the tube, a breech 45 in the tube adapted to receive an explosive charge, a piston slidably mounted in the tube, and a male cutting die carried by the piston for movement into working relation with the female die, one of the sealing discs being positioned to hold the male cutting die against such movement until a desired force is created by the expanding gases of a detonated explosive charge. 50
15. In combination, a barrel, a plate secured in transverse perpendicular relation to the barrel, a second plate, work receiving means, cap screws for removably holding the plates in spaced parallel relation with the work receiving means therebetween in alignment with the barrel, a unit removably positioned in the barrel, a breech block 55 releasably holding the unit in the barrel, and means associated with the breech block for detonating an explosive charge carried by the unit, said unit including a tube, means removably sealing the tube, a breech in the tube adapted to receive an explosive charge, a piston slidably mounted in the tube, and a working tool carried by the piston for movement into working relation with the work receiving means. 60
16. In combination, a barrel, a plate secured in transverse perpendicular relation to the barrel, a second plate, work receiving means, cap screws for removably holding the plates in spaced parallel relation with the work receiving means therebetween in alignment with the barrel, a unit removably positioned in the barrel, a breech block releasably holding the unit in the barrel, and means associated with the breech block for detonating an explosive charge carried by the unit. 65
17. A unit for use in explosively actuated apparatus comprising in combination a tube, sealing discs removably clamped at the ends of the tube, a breech in the tube adapted to receive an explosive charge, said tube being of insufficient strength to withstand the discharge of the explosive means without support, a piston slidably mounted in the tube, and a working tool carried by the piston for movement therewith, one of the sealing discs being positioned to hold the working tool and piston against movement until a desired force is created by the expanding gases of the detonated explosive charge received by the breech. 70

ROBERT TEMPLE, JR.
